UNITED STATES PATENT OFFICE.

ISIDOR FREID, OF BROOKLYN, NEW YORK.

DESIGN FOR A TRAY.

50,885.

Specification for Design.

Patented June 5, 1917.

Application filed March 20, 1917. Serial No. 156,209. Term of patent 7 years.

To all whom it may concern:

Be it known that I, ISIDOR FREID, a citizen of the United States, residing at New York, borough of Brooklyn, in the county of Kings and State of New York, have invented a new and ornamental Design for a Tray, of which the following is a specification, reference being had to the accompanying drawing, forming part thereof.

The figure is a perspective view of a tray showing my new design.

I claim:

The ornamental design for a tray as shown.

ISIDOR FREID.
